VANE PUMP CONSTRUCTION

William G. Finlayson, Harry H. Brown, and Joseph J. McGinnis, Detroit, Mich., assignors to Vickers Incorporated, Detroit, Mich., a corporation of Michigan

Application March 29, 1946, Serial No. 658,108

3 Claims. (Cl. 103—135)

1

This invention relates to power transmissions, particularly to those of the type comprising two or more fluid pressure energy translating devices, one of which may function as a pump and another as a fluid motor.

The invention is more particularly concerned with a vane pump construction particularly adapted for use in hydraulic power transmission systems.

In the patent to Vickers No. 1,989,900, there is disclosed a rotary vane pump which has found wide commercial use in its field. In a pump of this type, the working chambers are defined by a generally oval cam ring and a slotted rotor carrying a plurality of radially slidable vanes contacting the ring. Pumps of this construction have been found eminently suitable as sources of high pressure fluid for power purposes over a fairly wide range of operating conditions. However, one limiting factor in their design has been found to be the rate of wear between the outer ends of the vanes and the elliptical surface of the ring. Although a certain amount of wear, at this point, is permissible without interfering with the efficiency of the pump, it has been found that when certain limiting speeds, pressures, and volumetric capacities are exceeded that the wear rate is so great as to be economically unfeasible.

One of the principal reasons for the success of such pumps lies in the fact that a very large amount of wear on the ends of the vanes and to some extent also on the ring can be permitted with only a very slight effect on the efficiency of the pump. This, of course, is due to the fact that the vanes are maintained in contact with the ring by centrifugal force and fluid pressure and that the pumping action is independent of how much the tips of the vane have been worn off. However, if the rate of wear is excessive, the pump life becomes too short to be commercially acceptable. Consequently, pumps of this construction have heretofore been limited in their ratings to maximums in the neighborhood of 1000 pounds per square inch pressure, 1800 revolutions per minute and 60 gallons per minute delivery. While many attempts have been made to construct satisfactory pumps of this type with higher ratings than this, none have been successful prior to the present invention.

It is an object of the present invention, therefore, to provide an improved rotary vane pump construction having a far lower rate of wear at the critical surfaces of the vanes and ring so that it is no greater than the wear rate on the

2

other parts of the pump such as the shaft bearings, end plates, etc.

A further object is to provide an improved pump construction which can be operated at far greater speeds, higher pressures and larger delivery rates and which will, in addition, have a longer life. These and other objects are accomplished by a construction wherein the fluid pressure forces acting on the vane in a radial direction are in substantially complete balance at all times during the cycle of rotation.

Further objects and advantages of the present invention will be apparent from the following description, reference being had to the accompanying drawings wherein a preferred form of the present invention is clearly shown.

In the drawings:

Figure 1 is a longitudinal cross-section of a rotary vane pump embodying a preferred form of the present invention.

Figure 2 is a transverse cross-section of the working elements of the pump.

Figures 3 and 4 are fragmentary cross-sections corresponding to Figure 2 showing the parts in different positions.

Figure 5 is a cross-section on line 5—5 of Figure 2.

Figure 6 is a cross-section on line 6—6 of Figure 2.

Referring now to Figure 1, there is shown a main pump body 10 having concentric annular passages 12 and 14 which communicate, respectively, with outlet and inlet pump connections of usual form. The housing 10 may be supported on a mounting bracket 16 secured thereto by bolts 18. Formed in the housing 10 is a cylindrical cavity 20 adapted to be closed by an end-cap 22 secured to the housing 10 by bolts 24. Journalled on bearings 26 and 28 in the housing and end-cap, respectively, is a drive shaft 30 having a splined drive portion 32 intermediate the bearings.

Mounted within the cavity 20 is a pump cartridge generally designated 34. The cartridge 34 comprises a pair of similar flanged bushings 36 preferably formed of bearing material such as bronze. The bushings 36 are provided with four arcuate openings or ports 38 and 40 arranged in diametrically opposed pairs. The ports 38 of the right-hand bushing in Figure 1 communicate with the outlet or pressure passage 12 by means of cored passages indicated at 42. Likewise, the ports 40 communicate with the inlet or suction passage 14 by cored passages 44.

Radially inward of the ports 38, the inner

face of the bushing is provided with a pair of recesses 46 which communicate with the ports 38 by means of grooves 48. The ports 38 and 40 extend completely through the flange of the bushings whereas the recesses 46 and grooves 48 are formed in the inner face only as seen more clearly in Figure 6. The ports 38 at one end are provided with extensions 50 in the nature of restricted grooves in the face of the bushings and similar grooves 52 are provided at one end of the recesses 46. Preferably, the grooves 52 are somewhat longer and of much smaller cross-section than the grooves 50 for a purpose later to be described.

Radially inward of the ports 40 there are formed a pair of ports 54 which extend through the bushings from face to face and communicate with the ports 40 on the outer face of the bushings by a wide groove 56 as seen more clearly in Figure 5.

The cartridge also comprises a cam ring 58 of hardened steel, or high grade cast iron such as "meehanite" which lies between the flanges of the bushings 36 and closely fits the cylindrical recess 20 of the housing. The ring 58 has a cam track of generally elliptical form which preferably is formed of two circular arcs on its minor diameter extending from the edge of port 38 to the edge of port 40, two other circular arcs on its major diameter extending between ports 38 and 40 together with two inlet and two outlet ramps connecting these arcs by a suitably curved surface. The main body 10, bushings 36 and ring 58 together may be considered to form a housing for the moving parts of the pump.

Journalled in the tubular portion of the bushings 36 is a rotor 60 having a plurality of substantially radial vane slots 61 formed in its periphery. The vane slots are slightly inclined with their outer ends forward of their inner ends in the direction of rotation in the preferred form illustrated. The inner ends of the vane slots register in turn during rotation of the rotor with the recesses 46 and ports 54, the latter constituting what may be termed slot outlet and slot inlet ports, respectively. Positioned in each of the slots are flat rectangular vanes 62 of hardened steel which are of the same width as the rotor and ring and which are freely slidable in and out in the slots. The outer edge of each vane 62 is preferably bevelled so that it contacts the ring only at the trailing edge and for this purpose, the vanes may be bevelled either to a very sharp edge or to a slightly dulled one which presents only a minute contact area to the ring 58.

The central chamber of the pump in which the shaft 30 is located may be connected to the inlet passage 14 by a suitable drain conduit 64 and a shaft seal 66 provided adjacent to bearing 28.

In operation, when the shaft 30 is driven counterclockwise in Figures 2, 3, and 4, fluid will be taken in through the pump inlet and suction ports 40 to the working chambers between the rotor and ring in the well-known manner. The vanes will carry this fluid across the lands in the bushings between ports 40 and 38 and deliver it to the outlet ports 38 and pump outlet passage 12. In this respect, the action is identical to that described in more detail in the Vickers patent previously referred to.

The greatly improved wear characteristics of the present construction are obtained by the arrangement shown for controlling the application of pressure to the bottom of the vane slots. Considering clockwise rotation, the ends of ports

40 and 54 shown in Figure 3 may be termed trailing edges (as respects the vanes sweeping past them) and the extensions 50 and 52 may be considered the leading edges of ports 38 and 40. As more clearly shown in Figure 3, each vane as it leaves the trailing edges of the suction ports 40 is simultaneously cut off from the slot suction ports 54. As the rotor advances to the position shown in Figure 4, the slot is first connected to the slot outlet ports 46 through the restricted extensions 52. This enables a gradual build-up of pressure at the inner end of the vane to occur, and, at about the same time or preferably just slightly later, the vane ahead of the one under consideration passes on to the restricted extension 50 of the main outlet port 38. This admits pressure to the working chamber which, although full of oil, was previously at suction pressure. Due to the very slight compressibility of oil, a very slight flow will take place through the restricted passage 50 and compress the oil in the working chamber up to delivery line pressure. The design of the restricted passages 50 and 52 is such that having regard to the volume to be compressed in the working chamber and the volume to be compressed at the inner end of the vane slot, the pressure build-up at both points occurs at the same rate and simultaneously.

It will be noted that due to the bevel on the leading edge of the vane tip that the pressure in the working chamber acts radially inward over substantially the full cross-sectional area of the vane and this is balanced by a similar pressure acting at the inner ends of the vane slots. Thus, substantially, the only force acting on the vane is that due to centrifugal force. It will also be noted that the bevel at the tip of the vane forms an oil film wedge which assists in lubricating the point of contact between the vane tip and the ring, thus giving the vane a tendency to "ski" on a film of oil.

While the form of embodiment of the invention as herein disclosed constitutes a preferred form, it is to be understood that other forms might be adopted, all coming within the scope of the claims which follow.

What is claimed is as follows:

1. A rotary vane pump comprising a housing having a generally elliptical working chamber provided with a pair of diametrically opposite main inlet ports and a pair of diametrically opposite main outlet ports, a rotor in the chamber having a plurality of generally radial vane carrying slots, vanes slidable in the slots and having their outer ends bevelled to contact the surface of the working chamber at their trailing edges, a pair of diametrically opposite slot inlet ports and a pair of diametrically opposite slot outlet ports positioned to register with the inner ends of said slots, said housing providing a first pair of lands between the trailing edges of the main inlet ports and the leading edges of the main outlet ports, and a second pair of lands between the trailing edges of the slot inlet ports and the leading edges of the slot outlet ports, the first pair of lands extending over a greater arc than the second pair by substantially the arc between adjacent vanes whereby pressure is applied to both inner and outer ends of the vanes at the same instant, the main and slot outlet ports having a restricted portion adjacent their leading edges to cause a gradual build-up of pressure as the vanes and the inner ends of the slots,

respectively, establish communication with the outlet ports.

2. A rotary vane pump comprising a housing having a generally elliptical working chamber provided with a pair of diametrically opposite main inlet ports and a pair of diametrically opposite main outlet ports, a rotor in the chamber having a plurality of generally radial vane carrying slots, vanes slideable in the slots and having their outer ends bevelled to contact the surface of the working chamber at their trailing edges, a pair of diametrically opposite slot inlet ports and a pair of diametrically opposite slot outlet ports positioned to register with the inner ends of said slots, said housing providing a first pair of lands between the trailing edges of the main inlet ports and the leading edges of the main outlet ports, and a second pair of lands between the trailing edges of the slot inlet ports and the leading edges of the slot outlet ports, the first pair of lands extending over a greater arc than the second pair by substantially the arc between adjacent vanes whereby pressure is applied to both inner and outer ends of the vanes at the same instant, the main and slot outlet ports having a restricted portion adjacent their leading edges to cause a gradual build-up of pressure as the vanes and the inner ends of the slots, respectively, establish communication with the outlet ports, the restricted portion at the slot outlet port being smaller than the restricted portion at the main outlet port.

3. A rotary vane pump comprising a housing having a generally elliptical working chamber provided with a pair of diametrically opposite main inlet ports and a pair of diametrically opposite main outlet ports, a rotor in the chamber having a plurality of generally radial vane carrying slots, vanes slideable in the slots and having their outer ends bevelled to contact the surface

of the working chamber at their trailing edges, a pair of diametrically opposite slot inlet ports and a pair of diametrically opposite slot outlet ports positioned to register with the inner ends of said slots, said housing providing a first pair of lands between the trailing edges of the main inlet ports and the leading edges of the main outlet ports, and a second pair of lands between the trailing edges of the slot inlet ports and the leading edges of the slot outlet ports, the first pair of lands extending over a greater arc than the second pair by substantially the arc between adjacent vanes whereby pressure is applied to both inner and outer ends of the vanes at the same instant, the main and slot outlet ports having a restricted portion adjacent their leading edges to cause a gradual build-up of pressure as the vanes and the inner ends of the slots, respectively, establish communication with the outlet ports, the restricted portion at the slot outlet port being smaller than the restricted portion at the main outlet port.
